(57) **CLAIM**

The ornamental design for a spa jet flange, as shown and described.

DESCRIPTION

FIG. 1 is a top side perspective view of a spa jet flange showing our new design on a first jet housing.

FIG. 2 is a front view of the design shown in FIG. 1.

FIG. 3 is a rear view of the design shown in FIG. 1.

FIG. 4 is a left side view of the design shown in FIG. 1.

FIG. 5 is a right side view of the design shown in FIG. 1.

FIG. 6 is a top view of the design shown in FIG. 1.

FIG. 7 is a bottom view of the design shown in FIG. 1.

FIG. 8 is a top side perspective view of a spa jet flange showing our new design on a second jet housing.

FIG. 9 is a front view of the design shown in FIG. 8.

FIG. 10 is a rear view of the design shown in FIG. 8.

FIG. 11 is a left side view of the design shown in FIG. 8.

FIG. 12 is a right side view of the design shown in FIG. 8.

FIG. 13 is a top view of the design shown in FIG. 8.

FIG. 14 is a bottom view of the design shown in FIG. 8.

FIG. 15 is a top side perspective view of a spa jet flange showing our new design on a third jet housing.

FIG. 16 is a front view of the design shown in FIG. 15.

FIG. 17 is a rear view of the design shown in FIG. 15.

FIG. 18 is a left side view of the design shown in FIG. 15.

FIG. 19 is a right side view of the design shown in FIG. 15.

FIG. 20 is a top view of the design shown in FIG. 15; and,

FIG. 21 is a bottom view of the design shown in FIG. 15. The broken lines show portions of the spa jet flange that form no part of the claimed design.

1 Claim, 20 Drawing Sheets
